UNITED STATES PATENT OFFICE.

HAROLD E. McCRAY, OF WATERLOO, IOWA, ASSIGNOR TO JOHN DEERE TRACTOR COMPANY, OF WATERLOO, IOWA, A CORPORATION OF IOWA.

INTERNAL-COMBUSTION ENGINE.

Original application filed February 15, 1923, Serial No. 619,081. Divided and this application filed April 27, 1925. Serial No. 26,155.

My invention relates to internal combustion engines of the horizontal type such as are commonly used for operating farm machinery, and my present application, which 5 is a division of my pending application, Serial No. 619,081, filed February 15, 1923, and issued Nov. 8, 1927, as Patent No. 1,648,737 has particularly to do with the supplying of fuel to the engine cylinder. 10 It has for its object to provide an improved construction which will be simple in design, economical of manufacture, and which will operate efficiently to supply a mixture of air and gasoline, or equivalent hydrocarbon 15 fuel, to the engine cylinder. I accomplish this object as illustrated in the drawings and as hereinafter described. What I regard as new is set forth in the claims.

In the accompanying drawings,

20 Fig. 1 is a side elevation of an internal combustion engine of the type referred to equipped with the improvements that constitute the subject matter of this application;

25 Fig. 2 is a partial end view of that end of the engine at which the intake and exhaust valves are located; and

Fig. 3 is a partial horizontal section on line 3—3 of Fig. 2.

30 In the drawings I have illustrated my improvements applied to a single cylinder horizontal engine comprising a hollow base 4 in the form of a casting adapted to be bolted or otherwise secured to a supporting plate 5, of wood or other suitable material, and to contain within it a fuel tank 6 which 35 preferably occupies the greater portion of said base. Mounted upon the base 4 is a crank case 7 having a removable cover 8 secured by bolts 9, and integral with said crank case is a combined cylinder block and water hopper 10 through which a cylinder 11 extends horizontally, as best shown in Fig. 3 and indicated by dotted lines in Fig. 1. A crank shaft 12 extends transversely of the crank case 7 and is mounted 40 in suitable bearings in the side walls thereof, said crank shaft being connected by a pitman 13, indicated by dotted lines in Fig. 1, with a piston 14 operating in the cylinder 11, as also indicated by dotted lines in said figure. The crank shaft 12 preferably carries two fly-wheels 15, one at each side of

the engine, one of said fly-wheels being shown in Fig. 1. The wall of the cylinder block 10, with the cylinder 11, forms a water-holding chamber 16, as shown in Fig. 3, and a removable plug 16^a is provided in the bottom of the cylinder block for drawing off the water when desired. Electric 60 current for ignition purposes is furnished by a magneto 17 mounted on the crank case 7, as shown in Fig. 1.

The inner end of the cylinder 11 opens into the crank case 7, as usual, and its outer end is closed by a removable head 18 that is secured to the cylinder block by bolts 19 shown in Fig. 2. Said head contains an ignition chamber 20 and an exhaust chamber 21, both of which communicate with the cylinder 11. The cylinder head 18 has mounted upon it an intake valve 22 and an exhaust valve 23, the former of which normally closes an intake port leading from a mixer body, hereinafter described, while the latter closes a port leading to the exhaust chamber 21. As shown in Fig. 3, these two valve ports are formed in the inner face of the cylinder head 18, with the valves opening inwardly into the end of the cylinder. 80 By this construction, the clearance area of the cylinder can be reduced to a relatively small volume, which is desirable in stationary farm engines as it enables high compression pressures to be obtained, which assist in the proper combustion of the lower grade fuels. Moreover, because of the reduced clearance area obtained by thus locating the valve ports, the ignition chamber 20 can be formed in the removable head 90 separately from the intake passageway without increasing the clearance volume objectionably. This separation of the ignition chamber from the intake passageway prevents the carbon and other residue of unburned fuel 95 oil, which tends to accumulate in the ignition chamber, from collecting on the intake valve seat. The valves 22 and 23 are normally held seated by springs 24, 25 mounted on the stems 26, 27 of said valves 100 respectively, as shown in Fig. 3. A muffler 28 is connected with the exhaust chamber 21, so that the exhaust gases are discharged therethrough. The construction of this muffler is not claimed hereinafter, as it forms 105 the subject matter of another divisional ap-

lication filed of even date herewith. Associated with the ignition chamber 20 are make and break ignition devices, indicated generally by the reference numeral 29. This ignition apparatus comprises a block 29^a which enters the side wall of the ignition chamber and carries stationary and rocking electrodes 29^b and 29^c for obtaining the make and break ignition operation characteristic of these stationary engines. The specific details of the ignition devices need not be described herein, as they also form the subject matter of a divisional application filed of even date herewith, my present invention being concerned only with the means for supplying a proper mixture of fuel elements to the ignition chamber 20. Valve operating devices, indicated generally by the reference numeral 30, serve to open the exhaust valve 23 at the proper time to permit spent gases in the cylinder 11 to be discharged through the exhaust chamber 21 and muffler 28.

The cylinder 11 is supplied with hydrocarbon liquid fuel from the fuel tank 6 through a pipe 31, the lower end of which is connected with an elbow coupling 32, which in turn connects with a pipe 33 leading from the lower portion of the tank 6 and provided with a check-valve 34. The coupling 32 and pipe 33 are located within the base 4, as shown in Fig. 1, so that they are well protected. The upper end of the pipe 31 connects with an intake nozzle or mixer body in the form of a pipe 35 that is integral with the cylinder head 18 and extends downward therefrom, as shown in Fig. 2, its open lower end being deflected laterally, as shown at 36 in Fig. 2, and being provided with a swinging lid 37 pivoted at 38, by which the open end of said mixer body may be wholly or partially closed to regulate the admission of air thereto. The pipe 31 connects with a plug 39 screwed into one side of the pipe 35 adjacent to the lower end thereof, which plug at its inner end is provided with a valve seat that is adapted to cooperate with the inner end of a needle valve 40 mounted in the opposite side of the pipe 35, as best shown in Fig. 1. Obviously by screwing the valve 40 in or out, the size of the fuel inlet opening may be varied to regulate the volume of liquid fuel admitted to the mixer body 35. The upper end of said mixer body communicates with the cylinder 11 through the port in the cylinder head 18 that is normally closed by the intake valve 22. It will be observed from Fig. 3 that the upper end of this mixer body or intake passageway is disposed in close proximity to the exhaust chamber 21, both substantially abutting each other with a single dividing wall intervening. This construction places these two passageways in close heat transmitting

relation, which has the desirable action of preheating the mixture passing up through the mixer body. The intake valve 22 is opened by the suction of the piston 14, provided the exhaust valve 23 is closed so that the suction is effected to open said intake valve, but as is well known to those familiar with the art, in engines of this type it is desirable, in order to economize fuel, to shut off the spark and hold the exhaust valve open while the fly-wheel continues to rotate above a critical speed. In other words, sometimes the fly-wheel can make quite a number of revolutions between explosions without dropping below its critical speed, and in such circumstances it is desirable to shut off the spark and hold the exhaust valve open so that fuel will not be drawn into the cylinder and consumed except as needed. When, however, the exhaust valve is closed, on the recessive stroke of the piston, the intake valve 22 is opened by the suction of the piston and a charge of fuel is drawn into the cylinder from the mixer body 35, the suction operating not only to draw fuel from the supply tank 6 through the pipe 31 and the valve controlled opening therefrom into said mixer body, but also to draw air in greater or less volume into said mixer body through the open lower end thereof. The fuel and air thus drawn into the mixer body will be mixed therein during their passage therethrough, so that when admitted to the cylinder 11 they will be in proper condition for effective combustion. It will be noted that the fuel is discharged into the mixer body 35 at right angles to the direction of its movement through said mixer body toward the cylinder, which is an advantageous feature, as by this means sufficient restriction is provided to make the engine operate effectively by suction to raise fuel from the base, which is at a lower level than the cylinder. By adjusting the air controlled plate or lid 37, and the needle valve 40, the mixer may be nicely regulated so as to secure the most efficient operation of the engine.

The feature of making the mixer body or intake nozzle an integral part of a removable cylinder head is an important one, as it contributes to economy of manufacture and maintenance, and to simplicity of design; and the same is true also of the arrangements provided for admitting fuel and air to the mixer body, and for regulating their mixture.

What I claim as my invention and desire to secure by Letters Patent, is—

1. In a single cylinder type of stationary internal combustion engine, the combination with a cylinder and piston, of a removable cylinder head having intake and exhaust ports formed in the inner face thereof, intake and exhaust valves controlling said

ports and having their valve stems projecting outwardly from the outer side of said cylinder head, an intake passageway integral with said head and communicating with 5 said intake port and with the atmosphere and comprising a mixer body formed integrally with said head, means for supplying fuel to said mixer body, an ignition chamber formed integrally with said removable head 10 and separately from said intake passageway, and make and break ignition devices in said chamber.

2. In a horizontal cylinder type of stationary internal combustion engine, the combination of a horizontal cylinder, a piston therein, a removable cylinder head having an intake port disposed substantially centrally in said removable head, an exhaust 15 port in said removable head disposed above and to one side of said intake port, an ignition chamber in said removable head disposed above and to the other side of said intake port, intake and exhaust valves for said ports respectively having their valve 20 stems projecting outwardly from the outer side of said removable head, make and break ignition apparatus in said ignition chamber, intake and exhaust passageways 25 communicating with said intake and exhaust ports, said passageways being in heat transmitting relation for preheating the entering mixture, said intake passageway comprising a mixer body formed integral with said head, and means for supplying the fuel to said 30 35 mixer body.

3. In a horizontal cylinder type of stationary internal combustion engine, the combination of a horizontal cylinder, a piston therein, a removable cylinder head having an intake port disposed substantially centrally in said removable head, an exhaust 40 port in said removable head disposed above and to one side of said intake port, an ignition chamber in said removable head disposed above and to the other side of said intake port, intake and exhaust valves for said ports respectively having their valve stems 45 projecting outwardly from the outer side of said removable head, an ignition block entering said ignition chamber through the side wall thereof, and stationary and rocking electrodes entering said ignition chamber through said block.

4. In a horizontal cylinder type of stationary internal combustion engine, the combination of a horizontal cylinder, a piston therein, a removable cylinder head having an intake port disposed substantially centrally in said removable head, an exhaust 50 port in said removable head disposed above and to one side of said intake port, an ignition chamber in said removable head disposed above and to the other side of said intake port, intake and exhaust valves for said ports respectively having their valve 55 stems projecting outwardly from the outer side of said removable head, and make and break ignition apparatus in said ignition chamber.

HAROLD E. McCRAY.
